US0D1016737S

(12) **United States Design Patent** (10) **Patent No.:** **US D1,016,737 S**
(45) **Date of Patent:** **** Mar. 5, 2024**

(54) **PORTABLE RENEWABLE ENERGY SOURCE GENERATOR**

(71) Applicant: **Wilton Diamond Merritt**, Washington, DC (US)

(72) Inventor: **Wilton Diamond Merritt**, Washington, DC (US)

(73) Assignee: **Merritt IP Holdings, LLC**, Birmingham, AL (US)

(**) Term: **15 Years**

(21) Appl. No.: **29/771,257**

(22) Filed: **Feb. 22, 2021**

(51) **LOC (14) Cl.** **13-02**

(52) **U.S. Cl.**

USPC **D13/103**

(58) **Field of Classification Search**

USPC D13/101, 102, 103, 107, 108, 110, 118, D13/119, 123, 184, 199

(57) **CLAIM**

The ornamental design for a portable renewable energy source generator, as shown and described.

DESCRIPTION

FIG. 1 is a top perspective view of a first embodiment of a portable renewable energy source generator;

FIG. 2 is a front view thereof;

FIG. 3 is a rear view thereof;

FIG. 4 is a top view thereof;

FIG. 5 bottom view thereof;

FIG. 6 is a left side view thereof;

FIG. 7 right side view thereof; and,

FIG. 8 is a front view thereof, shown in an alternate state. The broken lines shown represent the portions of the portable renewable energy source generator that form no part of the claimed design.

1 Claim, 8 Drawing Sheets
